UNITED STATES PATENT OFFICE.

JOHN M. EWEN, OF CHICAGO, ILLINOIS, ASSIGNOR TO THE LUXFER PRISM PATENTS COMPANY, OF SAME PLACE.

DESIGN FOR A PRISM-PLATE.

SPECIFICATION forming part of Design No. 27,346, dated July 13, 1897.

Application filed June 15, 1897. Serial No. 640,936. Term of patent 14 years.

To all whom it may concern:

Be it known that I, JOHN M. EWEN, a citizen of the United States, residing at Chicago, in the county of Cook and State of Illinois, have 5 invented and produced a new and original Ornamental Design for Prism-Plates, of which the following is a specification.

My invention relates to a design for a prism-plate, and is illustrated in the accompanying 10 drawing, wherein is shown an elevation of a prism-plate containing my design.

The prism-lights are provided each with a series of prisms B B, and each of the central lights C C is hexagon-shaped. The side, top, 15 and bottom sections are pieces derived from cutting up the hexagons and are shaped as shown. These several prism-lights are ar-

ranged together in a plate by means of the zigzag-shaped opaque frame-pieces E and the short cross-pieces F.

The essential features of my design are found in a prism-plate consisting of a series of hexagon-shaped prism-lights and pieces cut from such hexagon-shaped lights and shaped as shown, having each on one side a series of prisms, and a frame composed of zigzag and short pieces, as shown.

I claim—

The design for a prism-plate substantially as shown and described.

JOHN M. EWEN.
